(57) **CLAIM**

The ornamental design for a 2 in 1 USB cable, as shown and described.

DESCRIPTION

FIG. 1 is a perspective view of a 2 in 1 USB cable showing my new design in an unextended position;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a 2 in 1 USB cable in an extended position.

Those portions of the figures that are presented in broken lines merely illustrate the environment of the design and are not part of the claimed design.
